Inventor

UNITED STATES PATENT OFFICE.

OSCAR KRATZ, OF DETROIT, MICHIGAN, ASSIGNOR TO HAMILTON CARHARRT, MANUFACTURER, OF DETROIT, MICHIGAN, A CORPORATION OF MICHIGAN.

OVERALLS.

1,152,323.

Specification of Letters Patent. Patented Aug. 31, 1915.

Application filed March 24, 1915. Serial No. 16,723.

To all whom it may concern:

Be it known that I, OSCAR KRATZ, a citizen of the United States, residing at Detroit, Wayne county, and State of Michigan, have invented and discovered certain new and useful Improvements in Overalls, of which the following is a specification.

The usual mode of shoulder suspension for garments, such as overalls and the like, 10 involves the use of two straps crossed and stitched together at the back, with the ends of the straps below the point of crossing independently connected to the garment. This 15 method of construction and connection of the suspenders involves the use of especially provided material, forming relatively long straps, and requires labor incident to the formation of at least three points of connection.

20 It is the essential object of the present invention to eliminate two of such points of connection and to reduce the amount of material required for the straps, while improving the form of connection for increasing its strength and durability.

With these and further objects in view, as will in part hereinafter become apparent and in part be stated, the invention comprises certain novel constructions, combinations and arrangements of parts, as subsequently specified and later pointed out in the claims.

30 In the accompanying drawing, Figure 1 is a view in elevation of parts embodying the features of the present invention, Fig. 2, a fragmentary view of the suspender straps illustrated as arranged just prior to application to the garment, and Fig. 3, a vertical section taken on the plane indicated by the 35 line 3—3 of Fig. 1.

Referring to the drawing by numerals, 1 indicates a fragment of the rear upper edge portion of a pair of overalls, or other like garment. The edge contour of the garment 1 45 varies from the conventional garment in that the middle portion is extended and tapered upward to form a tab or projection 2, said tab preferably not being extended to a distance sufficient to terminate in a point, 50 but being truncated to form a straight edge portion 2'. Extending on the opposite sides of the projection 2 are the terminal flaps 3, 3, of suspender straps 4, 4. The said straps, instead of extending beyond the point of 55 crossing, merely lap each other on the angle

incident to the appropriate location of the straps, and the terminal flap portions 3 of said straps are respectively tapered so that the end of each is formed with an edge paralleling the outer edge of the other. The 60 parts referred to as terminal flaps 3 may be considered those portions of the straps 4 which extend below the transverse median line of the lapping portions of the straps, the said median line lying below the straight 65 edge portion 2' of projection 2. The straps 4 are stitched together by stitching 5, which extends along each edge of each strap for substantially the full distance of the lapping portion of the straps, with the result 70 that the stitching 5, which connects the terminal flaps 3 together, also connects said flaps with the interposed material of projection 2. It is, of course, obvious that 75 straps 4 are arranged in their proper location with respect to the projection 2 before the stitching 5 is applied, at least with respect to those portions of the stitching 5 extending along the edges of the flaps 3. Merely as a matter of convenience of assem- 80 blage, the straps 4 may be united by stitching 5 along their edges down to the transverse median line of the overlapping portion and then applied to the garment 1, and the balance of the stitching 5 then formed 85 through the flaps 3 and projection 2. This mode of practising the invention as suggested is clearly indicated in Fig. 2, and is effective in enabling the construction of the 90 straps by different operatives from those constructing the body of the garment, and also enabling the assemblage of the parts by still different operatives. As a means of further strengthening the connection of the 95 parts, stitching 5' is preferably provided through the flaps 3 and projection 2 of garment 1, and extends along the transverse median line of the lapping portions of the 100 straps.

As the stitching at its uppermost point is frequently subjected to considerable shearing stress, a rivet 6 of metal may be employed at this point and caused to penetrate the two straps to aid in firmly retaining the 105 straps in their given relation.

Having thus fully described my said invention, what I claim as new and desire to secure by Letters Patent, is:

1. The combination, with a garment, of suspender straps therefor having lapping 110

portions, parts of the lapping portions of the straps also lapping portions of the garment, and means for connecting the lapping portions of the straps fast together and to the garment, substantially as set forth.

2. The combination, with a garment formed with a tapering portion upstanding from the body of the garment, suspender straps having crossing portions disposed 10 with parts of the crossing portions lapping parts of said tapering portions, and means for securing the lapping portions together and to the material of the tapering portion, substantially as set forth.
- 15 3. The combination, with a garment, of suspender straps having lapping portions disposed on each side of the material of the garment, and means for securing the lapping portions fast together and to the material of the garment, substantially as set forth.
- 20 4. The combination, with a garment, of suspender straps disposed in angular relation

to each other and one end portion of each overlapping an end portion of the other, material of the garment being disposed between the lapping end portions, and stitching connecting said lapping end portions and penetrating the interposed material of the garment, substantially as set forth. 25

5. As a new article of manufacture, a pair of suspender straps crossing each other at one end and terminating at the crossing and being connected at the upper portion of the crossing leaving terminal flaps adapted to 30 be fastened together and to a portion of a garment connected therebetween, substantially as set forth.

In witness whereof, I have hereunto set my hand and seal at Detroit, Michigan this 40
16th day of March, A. D. nineteen hundred and fifteen.

OSCAR KRATZ. [L.S.]
